UNITED STATES PATENT OFFICE.

ROBERT WATSON, OF WASHINGTON, DISTRICT OF COLUMBIA, ASSIGNOR
OF ONE-HALF TO CHARLES A. KRAM, OF SAME PLACE.

APPARATUS FOR TREATING DISEASES OF THE EAR.

SPECIFICATION forming part of Letters Patent No. 660,233, dated October 23, 1900.

Application filed October 19, 1898. Serial No. 694,032. (No model.)

To all whom it may concern:

Be it known that I, ROBERT WATSON, a citizen of the United States, residing at Washington, in the District of Columbia, have invented certain new and useful Improvements in Apparatus for Treating Diseases of the Ear, of which the following is a specification.

My invention relates to improved means for giving massage treatment to the ear-drum; and it comprises an earpiece, one end of which is adapted to fit into the outer ear, said earpiece being made hollow, so as to form an air-chamber, means for compressing the air within said chamber, so as to force the ear-drum inward, a vent for releasing the air after compression, means for rarefying the air within the chamber, so as to draw the ear-drum outward, and an inlet arranged to admit air into the chamber after rarefaction.

The instruments at present in use designed to give massage treatment to the ear-drum in general consist of a tubular earpiece, within which the air is vibrated by means of a diaphragm or a close-fitting plunger; but such instruments are defective in that if the air is compressed against the ear-drum by the inward movement of the diaphragm or plunger there is only expansion and no rarefaction of the air upon its outward movement, such as is necessary to draw the ear-drum outward and conversely. If the plunger be started from its inmost position, there is rarefaction, but no subsequent compression, of the air within the chamber.

By my improvements I provide means for equalizing the air-pressure within and without the chamber at the end of the stroke of the plunger, so that compression and rarefaction of the air may both take place.

In the accompanying drawings, which are illustrative of my invention, Figure 1 is a side view of the preferred form of my instrument, showing it connected to a battery and a circuit-breaker. Fig. 2 is a central longitudinal section through the instrument shown in Fig. 1. Figs. 3 and 4 are similar views of modifications, and Fig. 5 is a section on the line 5 5 of Fig. 4.

In the form of my apparatus shown in Figs. 1 and 2, 1 indicates an earpiece having a tapering forward end 2, adapted to fit into the

ear. The earpiece is bored out centrally, as shown at 3, thus forming a laterally-inclosed air-chamber, which is open at its forward end. This earpiece is made of iron, and its larger end is surrounded by a helix 4, which is electrically connected by wires 5 to a battery or other source of electricity 6 and a suitable circuit-breaker 7. As shown, the helix is wound upon a tubular casing 8 of non-magnetic material, which fits the earpiece closely, and the helix projects a short distance above the end of the earpiece. Within the tubular casing 8, which forms a part of the air-chamber, is an iron plunger 9, which fits the casing closely, but yet is free to be moved longitudinally therein without undue friction. The plunger is attached by tension-springs 10 to a cap 11 upon the outer end of the tubular casing. A regulating-screw 12 extends through the center of the cap and limits the outward movement of the plunger. It will be seen that when current is sent from the battery through the helix the plunger 9 will be drawn inward toward the earpiece against the action of the springs 10 and that as soon as the circuit is broken the springs 10 will draw the plunger against the screw 12.

If the plunger were solid and no means provided for the passage of air to and from the chamber 3, it will be seen that if the smaller end 2 of the earpiece were fitted tightly within the ear the inward movement of the plunger would compress the air and upon its return movement the air would expand until it regained its normal pressure and there would be no suction upon the ear-drum, or if the plunger were assumed to start from its inward position there would be suction during its movement outwardly, but no compression of the air within the chamber upon its return.

In order to have the air within the chamber alternately compressed and rarefied, I provide valves which are arranged to equalize the pressure within and without the chamber at each end of the stroke of the plunger. As shown in Fig. 2, the plunger is provided with two openings 13 and 14, the opening 13 having a conical valve-seat 15 at its outer end and the opening 14 having a similar valve-seat 16 at its inner end. A conical valve 17

is fitted to the valve-seat 15, and it is provided with a stem 18, extending through the opening 13 and projecting slightly beyond the inner face of the plunger. The valve is held against its seat by a suitable compression-spring 19. A similar valve 20 is arranged to fit the seat 16, its stem 21 projecting through the opening and extending slightly beyond the outer face of the plunger, the valve being held to its seat by a compression-spring 22. The adjusting-screw 12 is provided with a stop-plate 23 at its inner end, arranged to engage the end of the stem 21 when the plunger is in its outer position.

15 The operation is as follows: When the ear-piece is inserted into the ear, the circuit-breaker 7 is operated to complete and break the circuit as rapidly as is desirable, thus energizing and deenergizing the helix 4.

20 When the helix is energized, the plunger is drawn toward the ear-piece, thus compressing the air within the chamber during the movement of the plunger. When the latter has nearly reached its inmost position, the

25 valve-stem 18 comes in contact with the end of the ear-piece, thus forcing the valve 17 off of its seat and permitting the compressed air to escape through the vent or opening 13. When the circuit is interrupted, the springs

30 draw the plunger outward, and as soon as it starts on its return movement the spring 19 will force the valve 17 to its seat, and during the further outward movement of the plunger rarefaction of the air will take place

35 within the chamber and the ear-drum will be drawn outward. When the plunger approaches the outward limit of its stroke, the valve 20 becomes lifted from its seat by the contact of its stem 21 with the stop 23 and

40 air will rush in through the inlet 14 to the air-chamber. It will be seen that this action will be repeated as long as the completion and interruption of the current takes place. The stroke of the plunger can be lengthened

45 or shortened by means of the regulating-screw 12.

In the arrangement shown in Fig. 3 instead of employing spring-pressed valves in the plunger the latter is formed with a central bore 25, which, as shown, extends from its inner face nearly to the opposite end of the plunger and with two small openings 26 and 27 arranged one above the other and extending from the opening 25 radially outward

50 through the plunger. The casing 8 is provided with a perforation 28, with which the inlet-opening 27 in the plunger registers when the latter is in its outermost position, as shown in Fig. 3, and with which the vent-opening

55 26 registers when the plunger is in its innermost position. The plunger travels on guide-rods 29, which prevent it from turning within the casing. By means of the screw 12 the outward movement of the plunger is limited,

60 and it may readily be adjusted so that the opening 27 will register with the perforation 28. The distance between the openings 26

and 27 is just equal to the length of stroke of the plunger, so that when the latter has reached its inmost position the opening 26 will register with the opening 28. Inward and outward movements of the plunger are effected in the same manner as in the form shown in Fig. 2. When the plunger moves inward from the position shown in Fig. 3, the opening 27 will be out of register with the perforation 28, and until the vent-opening 26 comes opposite said perforation the air will be compressed within the air-chamber. When, however, the plunger has reached its inmost position, the air will escape through the openings 25 and 26 and the perforation 28. Upon the following outward movement of the plunger no air will be admitted to the air-chamber until the inlet-opening 27 registers with the perforation in the casing. This action will be repeated as long as the current through the helix is completed and broken. In this form of apparatus the length of the stroke of the plunger is always the same. In order to vary the degree of compression and rarefaction within the chamber 3, I provide an opening 30, extending through the wall of the ear-piece into the chamber, through which air may escape and enter, the quantity of air passing through this opening being regulated by screw-valve 31.

In the form shown in Fig. 4 the plunger travels upon guide-rods 35, which are secured in the larger end of the ear-piece and united at their outer ends by a cap or cross piece 36. Instead of working within a casing, as in the devices shown in Figs. 2 and 3, the plunger in Fig. 4 has a central smooth-bored opening 37, extending from its inner face nearly to the outer end, and a tube 38, forming the air-chamber of the ear-piece, extends upwardly into the opening in the plunger. This tube is open at the top and is provided with perforations 39 and 40, with which a radial opening 41 in the plunger is adapted to register at the limits of its movement. The operation is very much the same as in the device shown in Fig. 3. When the plunger is in its outermost position, the air-chamber is in communication with the atmosphere through the inlet 40 and radial opening 41. If the plunger moves inward, this communication is shut off and compression of the internal air results until the limit of the stroke is reached, when the compressed air will escape through the vent 39 and opening 41. Upon the return of the plunger rarefaction of the internal air will take place until the opening 41 registers with the inlet 40. In this figure I have shown a regulating-valve 42 in the end of the plunger, by means of which the degree of compression and rarefaction may be regulated in the same way that it is regulated by the screw 31 in Fig. 3.

The plungers in any of the forms of apparatus shown may consist entirely of iron; but in order to make them light the outer parts of the plungers may be made of wood or other

- material suitably secured to the iron, if desired.
- The automatic mechanical opening and closing of the vent and inlet ports at precisely the proper time is an important feature in a motor-operated apparatus of this kind, where the amount of compression and rarefaction of the air is small and where these operations follow each other in very rapid succession.
- Without limiting myself to the forms of apparatus shown in the drawings, what I claim, and desire to secure by Letters Patent, is—
1. In an apparatus for treating diseases of the ear, the combination with a laterally-in-closed air-chamber, open at its forward end, said chamber having a vent, of a reciprocating plunger adapted to compress the air within the chamber, and means for automatically opening the vent to equalize the air-pressure within and without said chamber after compression has been effected.
  2. In an apparatus for treating diseases of the ear, the combination with a laterally-in-closed air-chamber open at its forward end, said chamber having an inlet, of a reciprocating plunger adapted to rarefy the air within the chamber, and means for automatically opening the inlet to equalize the air-pressure within and without said chamber after rarefaction has taken place.
  3. In an apparatus for treating diseases of the ear, the combination with a laterally-in-closed air-chamber open at its forward end, of a reciprocating plunger adapted to alternately compress and rarefy the air within the chamber, and means for automatically equalizing the air-pressure within and without said chamber after each operation of compression and rarefaction.
  4. In an apparatus for treating diseases of the ear, the combination with a laterally-in-closed air-chamber open at its forward end, said chamber having a vent, of a reciprocating plunger adapted to compress the air within the chamber, said plunger being adapted to open the vent after compression has been effected, to equalize the air-pressure within and without said chamber.
  5. In an apparatus for treating diseases of the ear, the combination with a laterally-in-closed air-chamber open at its forward end, said chamber having an inlet, of a reciprocating plunger adapted to rarefy the air within the chamber, said plunger also being adapted to open the inlet after rarefaction has been effected to equalize the air-pressure within and without said chamber.
  6. In an apparatus for treating diseases of the ear, the combination with a laterally-in-closed air-chamber open at its forward end, said chamber having a vent and an inlet, of a reciprocating plunger adapted to alternately compress and rarefy the air within the chamber, said plunger being adapted to open the vent and inlet after each operation of compression and rarefaction respectively, so as to equalize the air-pressure within and without the chamber.
  7. In an apparatus for treating diseases of the ear, the combination with a laterally-in-closed air-chamber open at its forward end, of a reciprocating plunger adapted to compress the air within the chamber, said plunger having a vent therein, and means for opening said vent after compression to equalize the air-pressure within and without said chamber. 75
  8. In an apparatus for treating diseases of the ear, the combination with a laterally-in-closed air-chamber open at its forward end, of a reciprocating plunger adapted to rarefy the air within the chamber, said plunger having an inlet therein, and means for opening said inlet after rarefaction to equalize the air-pressure within and without said chamber. 85
  9. In an apparatus for treating diseases of the ear, the combination with a laterally-in-closed air-chamber open at its forward end, of a reciprocating plunger adapted to alternately compress and rarefy the air within the chamber, said plunger having a vent and an inlet, and means for opening said vent and inlet after each operation of compression and rarefaction respectively, to equalize the air-pressure within and without said chamber. 95
  10. In an apparatus for treating diseases of the ear, the combination with a laterally-in-closed air-chamber open at its forward end, and means for alternately compressing and rarefying the air within said chamber, said chamber having a vent adapted to release the air after compression and an inlet adapted to admit air after rarefaction, of means for regulating the degree of compression or rarefaction within the chamber. 100
  11. In an apparatus for treating diseases of the ear, the combination with a laterally-in-closed air-chamber open at its forward end, and a reciprocating plunger adapted to alternately compress and rarefy the air within the chamber, said chamber having a vent adapted to release the air after compression and an inlet adapted to admit air to the chamber after rarefaction to equalize the air-pressure within and without said chamber after each 105 operation, of means for adjusting and limiting the movement of the plunger.
  12. In an apparatus for treating diseases of the ear, the combination with a laterally-in-closed air-chamber open at its forward end, and means for alternately compressing and rarefying the air within said chamber, said chamber having a vent and an inlet normally closed during the operations of compression and rarefaction, of automatic means for opening said vent after compression has been effected and for opening said inlet after rarefaction has been effected. 120
  13. In an apparatus for treating diseases of the ear, the combination with the laterally-inclosed air-chamber open at its forward end, said air-chamber having a vent, of means for

compressing the air within the chamber and for automatically opening said vent after compression to equalize the internal and external air-pressures.

- 5 14. In an apparatus for treating diseases of the ear, the combination with the laterally-inclosed air-chamber open at its forward end, said chamber having an inlet, of means for automatically rarefying the air within the

chamber and for automatically opening said ~~to~~ inlet to equalize the internal and external air-pressures after rarefaction has been effected.

In testimony whereof I affix my signature in presence of two witnesses.
